SLIDING-CLASP FASTENER

Tryggve B. Stue, Oslo, Norway; Ingrid Stue, executrix of said Tryggve B. Stue, deceased

Application November 7, 1949, Serial No. 125,905

Claims priority, application Norway March 5, 1949

7 Claims. (Cl. 70—68)

1

The present invention relates to improvements in sliding-clasp fasteners of the type in which the slider may be fixed by means of a lock device in the closed position of the fastening.

One object of the invention is to provide a locking device which may be used in connection with sliding-clasp fasteners of any type and which may be situated at the outer or inner side of the article which the fastening is intended to close.

A further object of the invention is to provide a lock, of simple construction and operable by a key, which lock can serve to secure the slider in an effective manner, and also in its released position may serve as a snap fastener for preliminary securing of the slider.

The invention accordingly provides a sliding clasp fastener of the kind referred to, which is characterised in that the slider has a projecting latch member insertable in the lock for co-operation therewith. The latch member may be connected to the slider so as to be turnable in the longitudinal direction thereof, and may further be provided at its upper side with an eye-like projection preferably produced by stamping and bending over of the material of the member.

A latch member as aforesaid may have at least one lateral recess or notch for co-operating with a detent member displaceably mounted in the lock. Desirably, the latch member may have a spatulate head with a neck affording opposite recesses adapted to be engaged by opposed detent members of the lock.

The invention further provides, for use with a sliding clasp fastener the slider of which has a latch member as aforesaid, a lock having at least one detent member movable transversely of the latch member into locked engagement with the latch member by guide means displaceable within the lock.

The or each detent member may be resiliently mounted or inherently resilient and thereby displaceable when unlocked into or from engagement with the recess or recesses in the latch member by insertion or extraction of the latch member into or from the lock.

Preferably, the lock has a detent member which is substantially U-shaped with resilient arms the free ends of which are each provided with a inwardly directed lug or projection, as by inward bending of the material of the arm, and the arms of such a detent member when unlocked may be adapted to assume an attitude such that the distance between the lugs on said arms is less than the width of the head of the latch member.

2

Such a detent member may be mounted in the lock with its base immovable, and a displaceable member or plate may present guide cheeks serving, on displacement of said member or plate to a locking position, to embrace the arms and positively secure the lugs or projections thereon in engagement with the neck of the latch member.

The invention further provides locking means for a sliding clasp fastener comprising the combination of a slider having a projecting latch member and lock for receiving said latch member, the lock having detent means adapted resiliently to engage or release the latch member or to be secured in positive locking engagement with said member as by actuation of a key.

The foregoing and other features of the invention will be more fully understood from the following description of an embodiment of a lock and slider assembly, by way of example, with reference to the accompanying drawing in which:

Figure 1 is a perspective view of the separated main components of the lock.

Figure 2 is a plan view of the assembly with the lock casing removed.

Figure 3 is a vertical, longitudinal section through the assembly as shown in Figure 2.

Figure 4 is a section of a detail taken along the line IV—IV of Figure 2, and

Figure 5 is a partial plan view of the assembly in the released position of the lock.

As shown in the drawing, portions 1 and 2 of an article, such as a bag or the like, are interconnectable by means of a sliding-clasp fastener the tapes or halves 3 of which are secured along the respective edges of said portions. The hook members of said halves are mutually interengaged or released by a slider 4 which at the upper side thereof is provided with an eye-shaped projection 5. To the slider 4, preferably turnable in the longitudinal direction thereof, about the eye of projection 5, is secured a latch member 6 serving to co-operate with a lock, being shaped as a preferably flat tongue, the outer or free end of which is provided with a spatulate head presenting side notches 8 which form a neck portion 9.

On its upper side the latch member 6 is provided with an eye- or hook-shaped projection 10 preferably produced by stamping out and bending over of the material of the latch member, in which projection 10 may be secured if desired a ring or the like serving as a handle.

The lock co-operating with the latch member 6 of the slider comprises an open, tray-like casing 11 (shown inverted) having end and side walls 12 and 13 respectively. In one of the end walls

3

is provided a slot-shaped aperture 14 adapted for insertion of the latch member 6, and the opposite end wall has a downwardly projecting securing tongue 15.

In the casing 11 is lodged a plate 16 of channel shaped cross section and of a length and width corresponding to the inner length and width respectively of the casing 11. Bent-up side portions 16' of the plate 16 serve to hold the plate at a certain distance from the top surface member of casing 11. At one end the plate 16 has a tongue 17 which is adapted to project through the aperture 14 in the end wall of the casing 11.

The lock is secured to the portions 1, 2 of the article by means of a clamping plate 18 placed at the inner side thereof, about one end of which plate is bent the tongue 17 protruding through the aperture 14, as shown in Figure 3, and about the outer end of which is bent the tongue 15 of the casing end wall 12 after having been passed through the material of the article. The plate 16 may also be provided with tongues 19 to be passed through the material of the article, inserted into corresponding slits 20 in the plate 18 and bent over as additional means of securing the plate 16 to the lock. As will be understood, the plates 16, 18 and the casing 11 may be interconnected in other ways and by other means, provided only that a reliable interconnection of the parts is obtained.

The inner plate 18 is at both sides of its front end by means of slits 21 provided with free portions 22 which by depression are bent into channel-shape, so that the edges 23 thereof are directed upwards, as shown. In mounting and securing the lock said edges 23 together with opposed portions of the edge of the apertured end wall 12 of the casing 11 are clamped upon the tapes 3 carrying the hook-members of the fastener, and between adjacent members thereon, whereby a reliable interconnection between the lock and the sliding-clasp fastener is obtained, and at the same time the effective length of the fastener may be limited, so that the usual stop members on the sliding clasp halves may be dispensed with.

Opposite the aperture 14, within the casing 11, the plate 16 is provided with parallel angle pieces 24, preferably stamped and bent upwardly from the material of the plate proper, having an intermediate space 25 adapted to receive the cross-piece 26 of a unitary U-shaped detent member, the springy branches or arms 27 of which have at their free ends each an inwardly protruding lug 28 produced as by turning in the material of the detent member. The parallel, vertical guiding cheeks 30 are provided with suitable intermediate spacing, at the end of a plate 31, serving as a locking plate, which is arranged upon the plate 16 and displaceable in the longitudinal direction thereof.

The cheeks 30 are provided by bending upwards portions of the material of the plate 31 proper, forming at the same time an opening 32 in which the angle-pieces 24 for securing the detent member extend upwards. At their outer ends the cheeks 30 may be stiffened outwardly by means of transverse angle pieces 30' constituted by upwardly bent end portions of the plate 31.

Further, the plate 16 is provided with an angle piece 33 bent to extend upwards through an aperture 34 in the movable locking plate 31 so as to limit the displacement thereof and serving at the same time to co-operate with a lock-

ing spring 35 which is secured between two bent up lugs 36, 37 provided at the inner end of the plate 31. In order to release and displace the locking plate 31 the spring 35 is in usual manner acted upon by a key inserted through a key hole in the casing 11 and guided by a pin 39 secured in the plate 16, which pin extends upwards through a longitudinal slot 40 in the locking plate 31.

For releasing the lock, the key is turned so that the spring 35 is displaced laterally until free of the angle piece 33 and the locking plate 31 is displaced rearwardly until the front end of the aperture 34 abuts against the angle piece 33, the side of the latter slidably abutting the free, inner end of the spring. During this movement the parallel guiding cheeks 30 are displaced backwards to such an extent that the arm 27 of the U-shaped blocking element are released and owing to their springiness are free to separate from each other so that the distance between the lugs 28 allows the head 7 of the latch member 6 to pass inwardly and outwardly, as shown in Figure 5. The springiness of the arms 27 is so arranged that in such released position thereof the distance between the bent ends 28 is somewhat smaller than the width of the head 7, whereby the blocking element in the released position of the lock may serve as a snap fastener for preliminary securing of the latch member 6.

For positively securing the member 6, the key is turned in opposite direction, whereby the plate 31 is moved in the reverse direction to the relative position shown in Figure 2, in which the guiding cheeks 30 embrace the arms 27 of the detent member and hold the lugs 28 thereof pressed into the side notches 8 of the latch member 6.

The device above described provides for reliable locking of the slider 4 by means of a lock which is simple and cheap to manufacture, which occupies little space, and which may be used in connection with sliding-clasp fasteners of all types.

The construction of the device which makes it possible to use the lock as a snap fastener engageable and releasable without the necessity for any special manual action upon the securing members, is evidently an advantageous and meritorious feature of the invention.

The detailed construction may be varied in many ways without departing from the scope of the invention. Thus the latch member 6 may be rigidly attached to the slider, either at the upper or lower side thereof. In the last mentioned case the lock may be positioned at the inner side of the article and a securing plate, provided with a key hole, at the outer side thereof, in which situation the lock is protected against injury of any kind. Further the lock may be provided at each end with an aperture such as 14 and two detent elements such as 27, 28, each co-operating with a locking plate in such manner that two sliders may be connected with the lock and secured therein, both by means of a single key, or each by means of a separate key, as may be desired. The latch member 6, if so desired, may be provided with a number of notches at each side, and each of the resilient or resiliently mounted arms 27 with a corresponding number of lugs or bendings.

I claim:

1. In a device for closing and locking a slide fastener, a latch member adapted to be secured to a slide of said fastener and having aligned notches

adjacent one end, a slideable locking member axially aligned with said latch member and having parallel guiding surfaces adjacent one end, a fixed member having a support thereon positioned intermediate said parallel guiding surfaces, and a U-shaped detent member mounted on said support and slidably received intermediate said parallel guiding surfaces and having loops at its ends initially engageable in the notches in the latch member and fully received therein when the locking member is slid towards the latch member.

2. In a device for closing and locking a slide fastener, a latch member adapted to be secured to a slide of said fastener and having aligned notches adjacent one end, a fixed base plate axially aligned with said latch member, a locking plate mounted upon said fixed base plate for slideable movement in the longitudinal direction of the latter and having parallel guide flanges adjacent one end, and a U-shaped detent member mounted on said fixed base plate and slidably received intermediate said parallel flanges and having loops at its ends initially engageable in the notches in the latch member and fully received therein when the locking plate is slid towards the latch member.

3. In a device for closing and locking a slide fastener, a latch member adapted to be secured to a slide of said fastener and having aligned notches adjacent one end, a base plate axially aligned with said latch member, a locking plate mounted upon said base plate for slideable movement in the longitudinal direction of the latter and having parallel guide flanges adjacent one end and end flanges at right angles to and abutting said guide flanges to prevent transverse bending of the latter, and a fixed U-shaped detent member slidably received intermediate said parallel flanges having loops at its ends initially engageable in the notches in the latch member and fully received therein when the locking plate is slid towards the latch member.

4. In a device for closing and locking a slide fastener, a latch member adapted to be secured to a slide of said fastener and having aligned notches adjacent one end, a lock casing having an aperture in one end receiving said latch member and a stationary base plate mounted within the lock casing and having parallel lugs thereon, a substantially U-shaped detent member mounted between said lugs and having its arms extending towards the said aperture in the end of the lock casing and loops at the ends of said arms initially engageable in the notches in the latch member, and a reciprocable plate mounted on said stationary base plate and having an elongated slot therein for receiving the parallel lugs on the base plate and parallel guide flanges thereon in slideable contact with the arms of the U-shaped detent member and adapted upon movement in one direction to force the loops on the said arms fully into the said notches in the latch member.

5. In a device for closing and locking a slide fastener, a latch member adapted to be secured to a slide of said fastener and having aligned notches adjacent one end, a lock casing having an aperture in one end receiving said latch member, a first plate within said lock casing adapted to be mounted on one side of a container to be closed by the slide fastener, a locking plate reciprocably mounted upon said first plate and having parallel guide flanges adjacent one end, a U-shaped

5
6
detent member mounted on said first plate and slidably received intermediate said parallel guide flanges and having loops at its ends initially engageable in the notches in the latch member and fully received therein when the locking plate is slid towards the latch member, and a third plate forming the bottom of said lock casing and adapted to be mounted on the other side of the container to be closed, said lock casing having thereon bent tongues securing the second plate in position.

6. In a device for closing and locking a slide fastener for hook members including tapes for carrying the hook members, a latch member adapted to be secured to a slide of said fastener, a lock casing having an aperture in one end receiving said latch member, a first plate within said lock casing adapted to be mounted on one side of a container to be closed by the slide fastener, means carried by said first plate engaging and locking said latch member, a second plate forming the bottom of said lock casing and adapted to be mounted on the other side of the container to be closed, said second plate having at one end transversely positioned channel shaped portions the free edges of which are adapted to cooperate with an end wall of the casing to clamp upon the tapes carrying the hook members of the slide fastener.

7. In a device for closing and locking a slide fastener for hook members including tapes for carrying the hook members, a latch member adapted to be secured to a slide of said fastener and having aligned notches adjacent one end, a lock casing having an aperture in one end and receiving said latch member, a first plate within said lock casing adapted to be mounted on one side of a container to be closed by the slide fastener, a locking plate reciprocably mounted upon said first plate and having parallel guide flanges adjacent one end, a U-shaped detent member mounted upon said first plate and slidably received intermediate said parallel guide flanges and having loops at its ends engageable in the notches in the latch member and fully received therein when the locking plate is slid towards the latter, and a third plate forming the bottom of said lock casing and adapted to be mounted on the other side of the container to be closed, said lock casing having thereon bent tongues securing the latter plate in position.
